UNITED STATES PATENT OFFICE

ALLAN S. BARROWS, OF LOS ANGELES, CALIFORNIA, ASSIGNOR TO THE YOUNGSTOWN STEEL DOOR COMPANY, OF CLEVELAND, OHIO, A CORPORATION OF OHIO

CAR DOOR

Application filed June 27, 1924. Serial No. 722,759.

This invention relates to improvements in car doors.

One of the objects of the invention is to provide a composite box car door including a braced metal frame of great strength and rigidity, in conjunction with closures or fillers of various kinds for the said frame, according to the type of door it is desired to use.

10 Another object of the invention is to provide a metal door frame which is arranged with a bed for the reception of panels or fillers of wood or other materials, the frame being constructed so as to take care of 15 stresses and strains upon the door in all directions and to prevent warping of the same, thus providing a door which has all the advantages of a heavy, all-steel construction, but resulting in a great reduction in weight 20 and expense.

Another object of the invention is to provide a door frame of unitary construction, in which the closures of various forms, such as wood or metal panels or fillers may be 25 readily applied thereto, the door in its assembled form having substantially the strength and rigidity of all-metal doors.

Other objects of the invention will more clearly appear from the description and 30 claims hereinafter following.

In the drawings forming part of this specification, Figure 1 is a broken, front elevational view of a car door of the character contemplated by my invention, parts of the 35 same being omitted to more clearly disclose the construction thereof. Figure 2 is a broken, enlarged horizontal sectional view of the invention substantially on the line 2—2 of Figure 1. Figure 3 is an enlarged vertical, 40 sectional view of the invention substantially on the line 3—3 of Figure 1. Figure 4 is an enlarged broken vertical sectional view, similar to Figure 3, of a modified form of my invention. Figure 5 is an enlarged broken, 45 horizontal sectional view of the invention shown in Figure 4, substantially similar to Figure 2. Figure 6 is an enlarged broken vertical sectional view, similar to Figure 3 of another modified construction. Figure 7 50 is a broken, front elevation of still another

modified form of my invention. Figure 8 is a sectional view of the invention on the line 8—8 of Figure 7. Figure 9 is a fragmentary sectional view similar to a portion of Figure 8 showing another slightly different application of my invention, and Figure 10 is a fragmentary sectional view, similar to Figure 9, of another modified form of my invention.

Referring to the drawings, A indicates the usual side angle of a door mounting of a 60 box car, B an angle at the opposite side of said door, C the top angle, and D a track upon which the door moves, rollers E being shown for this purpose, this being old and well known construction.

65 In the arrangement illustrated in Figures 1 to 5, inclusive, a sliding outside door is shown designated generally by reference character F. The invention herein contemplated resides in the door per se which is 70 hereinafter more particularly described, such door being of such construction as to be readily applied in connection with the usual standard mountings, the mountings herein shown being for the so-called "bottom hung" 75 door, but it will be readily understood that the door structure is equally well adapted for use in connection with the so-called "top hung" type of mounting.

80 Referring more particularly to the construction of the door F, such door is provided with top, bottom and side bars 20, 21, 22 and 23, respectively, and in this particular embodiment of the invention, are preferably in the form of T-bars, each including a medial flange 24, outer side flanges 25, and inner side flanges 26, the medial flanges 24 being all disposed toward the front of the car door, so that such flanges, in conjunction with the inner side flanges 26 of the T-bars, provide a 85 bed for the reception of panels or fillers of various kinds.

Braces 27 are preferably provided at the 90 rear face of the door F, which may be diagonally disposed as shown, and preferably in the form of tubes having their ends flattened as shown at 28, and secured to the inner flanges 26 of the T-bars 20 and 21, and to the inner flanges 26 of the T-bars 22 and 23, 95 as clearly shown in the Figures 1 to 3, it be- 100

ing noted that flattening the ends of the braces 27, and affixing the same to the inner sides of the inner flanges 26 of the T-bars, brings the outer surfaces of such braces substantially level with the inner surfaces of the T-bar frame. A transverse brace 29 is connected to the inner flanges 26 of the side bars 22 and 23, for strengthening the frame and serving as a means of connection for some of the panels disposed in the frame. The door in this form provides a braced bed of box-like form for the reception of suitable fillers, the sides of such bed being defined by the medial flanges 24 of the T-bars, and the bottom of such bed by the braces 27, and the inner side flanges 26 of the T-bars.

Adapted for disposition within the bed so provided is a door or panel 30, in this case being shown as wood, though other fillers may be used if desired, the door in this instance being provided with the usual reinforcing strips 31 along its edges on the inner surface of the door, as shown in the drawing, the strips 31, being preferably recessed to provide openings 32 for the reception of the braces 27, so that the inner surfaces of the door lie substantially flat upon the inner flanges 26 of the T-bars, and the outer surface of the door level with the outer edges of the medial flanges 24 of the T-bars. The panel 30 is preferably a wood car door of standard wood construction, being disposed in the bed as described, but of course other panels of various constructions can be utilized.

The panel 30 may be secured in position in the bed by any suitable means, bolts 32' being shown, and such bolts preferably have their heads 33 counter-sunk in the inner flanges 26 of the T-bars, and their stems extending through such flanges 26 and the adjacent edges of the panel 30, there being nuts 34 on the outer ends of the bolts 22 in the usual manner.

With this arrangement a door is provided which has great strength and rigidity, the door or panel 30 serving to brace the frame, and in turn being braced by the frame along its edges, and against lateral stress. The construction thus provided is economical in manufacture, and has all the advantages of expensive and heavy all-steel construction at a small portion of its cost.

Referring to the form of invention illustrated in Figures 4 and 5, inclusive, there is shown a construction generally similar to that just described, having T-bars 40 at its sides, and T-bars 41 and 42 at the top and bottom respectively, the medial flanges 43 of such bars being disposed outwardly as before, and having the inner flanges 44 and outer flanges 45 in the same positions. Braces 46, preferably in the form of tubular members, are provided, and have their ends flattened and fastened to the inner flanges 44

of the various T-bars as before explained. A cross brace 44' is mounted between the side bars 40 in the same manner as before described. In this embodiment of the invention, use is made of light filler sheets or closures in the form of metal plates 47, there preferably being two of the same utilized for each door. One of such sheets may have its outer and side edges 48 turned over the medial flanges 43 of the T-bars as shown, and secured in position by rivets, or other suitable fastening means. The inner edge of such sheet is preferably turned inwardly as shown at 49, and outwardly as at 50, so as to rest against the brace 44'. The inner edge of the opposite sheet 47, is also inwardly turned as at 52, and then outwardly at 53, such portion resting upon the outwardly turned portion 50 of the other sheet 47, the super-posed layers of material being secured to the cross brace 44' by means of rivets 54. The outer, and side edges 55 of the last named sheet are turned over the medial flanges 43 of the T-bars 40 and 41, and secured by suitable means, preferably rivets 56. By this arrangement a hollow metal door is provided having great strength and rigidity, and being very light in weight, and of small cost.

A slightly different construction is shown in Figure 6, there being provided the T-bars 40 in the same manner as described in Figures 5 and 6. Braces 46 are secured to the inner flanges of the T-bars as before explained, together with the cross brace 44'. Panels 60—61 in the form of thin metal sheets have their outer edges 62 turned over the flanges 43 of the T-bars of the frame, as shown in Figures 5 and 6, and secured thereto by rivets 63. The body portions of the panels 60 and 61 are preferably turned inwardly toward the braces 46 as shown at 64, and such body portions are corrugated or recessed as at 65 for the reception of the braces 46 as shown, so that the inner surfaces of such body portions of the panels are disposed substantially flush with the inner surfaces of the door frame. The meeting edges of the sheets 60—61 are preferably turned outwardly and inwardly as indicated at 66, overlap, and are fastened together by rivets 67, in this way providing a central reinforcing channel member 69. It should be here noted that with a construction of this character, the lading in the car is prevented from entering the framework of the door.

The embodiment of the invention shown in Figures 7 and 8, includes a unitary construction formed by notching the T-bars 80, 81 and 82, at their ends, as indicated in dotted lines, and welding the same together. The medial flanges 83 of such T-bars are disposed outwardly as before described, the inner flanges 84 and outer flanges 85 being provided in a like manner. A cross-piece preferably in the form of a T-bar 86, is provided, having

its ends welded to the flanges 84 of the side bars 80, and to the medial flanges 83 of such side bars. Gusset plates 84' are provided at the corners of the frame for strengthening the 5 same against torsional strain. In this form of the invention sectional beds are provided for the reception of fillers or panels of various kinds. In this instance sheet metal panel 87, and wood panel 88 are shown, and the 10 panel 87 may be provided with ventilating openings 89. The outer edges 90 of the panels 87 and 88 rest upon the inner flanges 84, and upon the side flanges 91 of the T-bar 86, and the panel 87 may be secured by rivets 92 15 and the panel 88 by countersunk bolts 93.

As may be understood, beds provided by the medial flanges 83, inner flanges 84 and the medial and side flanges 91 of the cross piece 86, are adapted for the reception of two metal 20 fillers, two wood fillers, or a metal and wood filler, like those just described. In Figure 9 there is shown a construction in which two wood fillers are used, the cross piece 93 and fragments of a frame being illustrated, it being understood that the remainder of the 25 frame is identical to that shown in Figures 7 and 8. In this embodiment it will be seen that the inner edges 94 of the wood fillers rest upon the medial flange 95 of the cross 30 piece 93, and upon the side flanges 96, there being bolts 97 extending through said side flanges 96 to secure the edges of the wood fillers in position, it being understood that the other edges of the fillers are also secured to 35 the inner flanges of the T-bars of the frame such as the flanges 84 shown in Figures 7 and 8. The remainder of the frame is of the character described heretofore and shown in Figures 7 and 8.

40 The construction illustrated in Figure 10, contemplates a cross piece 100 in the form of a Z bar, instead of the T-bar shown heretofore, and in this construction, one edge of a wood filler 101, is shown as disposed within 45 the turned flange 102 of the Z bar, and resting upon the web 103 of such bar, the oppositely turned flange 104 serving as a means upon which the edge of the metal panel 105 may be secured by suitable means such as rivets 106. 50 The remainder of the frame is of the same character as previously described and shown.

The above described modifications are but a few of a great variety, the purpose being to indicate the adaptability of a frame made up 55 in the form of a bed for the reception of a single panel, or for a plurality of sectional panels, the cross bar and frame serving in each instance to provide the beds for panels of various kinds, and means to which the 60 panels may be secured.

The important features of the invention reside in providing the beds for panels of various kinds, such as wood, sectional wood, metal, or metal and wood, and it is also pointed 65 out that by utilizing the T-bars in the con-

structions described and illustrated, the outer flanges of the T-bars serve as means for mounting the doors in standard mountings, while the medial flanges of the T-bars and the inner side flanges of such bars operate to 70 provide the beds for the panels. Attention is also called to the fact that the construction shown in Figures 7 and 8 is a unit, and may be sold in this form as an article of manufacture, it being necessary only to afterward apply the desired fillers to the door, and fasten them in position by suitable bolts or rivets, 75 apertures for such fastening means being provided in suitable locations.

I have herein shown and described what I 80 now consider the preferred manner of carrying out the invention, but the same is merely illustrative, and I contemplate all changes and modifications that come within the scope of the claims appended hereto.

I claim:

1. In a car door, the combination with a 85 door frame; of bracing members mounted adjacent one face of said frame, said frame and bracing members providing a bed; and a closure adapted for disposition in said bed, said closure having recesses for the reception of said bracing members; and means for securing said closure to said frame.

2. In a car door, the combination with a 90 door frame; of tubular bracing members mounted adjacent one face of said frame to provide a bed; and a closure adapted for disposition in said bed, said closure member having recesses for the reception of said bracing 95 members; and means for securing said closure to said frame.

3. In a car door, the combination with a 100 door frame; of bracing members mounted adjacent one face of said frame; and a closure adapted for connection to said frame and engagement with said bracing members, said closure having recesses for the reception of said bracing members; and means for securing 105 said closure to said frame.

4. In a car door, the combination with a 110 door frame; of diagonally disposed bracing members mounted adjacent one face of said frame and cooperating therewith to provide a bed; and a closure disposed in said bed and secured therein.

5. In a car door, the combination with a 115 door frame; of diagonally disposed bracing members mounted adjacent one face of said frame and cooperating therewith to provide a bed, and a closure disposed in said bed and secured therein, there being recesses in said closure for the reception of said bracing members.

6. In a car door, the combination with a 120 door frame; of bracing means disposed adjacent one side face of said frame and cooperating therewith to provide a bed; and a wood car door member disposed in said bed, said car door having reinforcing strips on 125 130

- its inner face, said strips being recessed for the reception of said first named bracing means; and means for securing said door member in said frame.
5. In a car door, the combination with a metal frame including T-bars having their medial flanges disposed outwardly; metal braces connected to the inner flanges of said T-bars; and fillers secured between the medial flanges of said T-bars and resting against said braces, said braces being in the form of tubular members having their ends flattened and secured to the inner flanges of said T-bars.
10. In a car door, the combination with a metal frame including T-bars having their medial flanges disposed outwardly; metal braces connected to the inner flanges of said T-bars; and fillers disposed between the medial flanges of said T-bars and resting against said braces, said braces being in the form of tubular members having their ends flattened and secured to the inner flanges of said T-bars, and said fillers being recessed for the reception of said tubular braces.
15. In a car door, the combination with a door frame comprising frame elements including portions extending substantially at right angles to the main plane of the door, and terminating in said plane at one side face of the door, and bracing members mounted adjacent the opposite side face of the door and forming with said frame elements a bed adapted for the broad side reception of a filler; a filler in said bed and lying within said extended portions of the frame; and means securing said filler to said frame.
20. As an article of manufacture, a unitary metal car door construction provided with frame members and means dividing the space bounded by said frame members to provide a plurality of separate beds, each of said beds being defined by metallic flanges extending in a plane substantially normal to the main plane of the door and terminating in said first mentioned plane, at one side face of the door, and extensions provided adjacent the opposite side face of the door and disposed at an angle to said flanges and forming the bottoms of said beds, each of said beds being arranged for the accommodation of a filler applied in a direction normal to the general main plane of the door.
25. In a car door structure of the character described, the combination with a door mounting; of a car door including side, top and bottom portions in the form of T bars with their medial flanges disposed outwardly; and mounting devices mounted on the car structure and engaging the outwardly projecting flanges of certain of said T bars to co-operate in maintaining said door in operative position.
30. In a car door comprising a frame made up of T bars, each having its medial flange disposed substantially normal to the main plane of the car; and a closure having marginal edge portions disposed at an angle to the remaining portions thereof and in substantial parallelism with the medial flanges of said T bars; and means for securing said angular marginal edges to the medial flanges of said T bars.
35. A car door comprising a frame made up of T bars, each having its medial flange disposed substantially normal to the main plane of the door; a closure mounted at one side face of the door and secured to the free edge portions of the medial flanges of said T bars; and bracing members arranged adjacent the opposite face of said door and connected to the inner flanges of said T bars.
40. In witness that I claim the foregoing I have hereunto subscribed my name this 5th day of June, 1924.
45. ALLAN S. BARROWS.
